UNITED STATES PATENT OFFICE.

JOSEPH HODGSON, OF PHILADELPHIA, PENNSYLVANIA, ASSIGNOR TO THOMAS DOLAN, OF SAME PLACE.

DESIGN FOR A SHAWL-FABRIC.

Specification forming part of Design No. 5,107, dated July 11, 1871.

To all whom it may concern:

Be it known that I, JOSEPH HODGSON, of Philadelphia, county of Philadelphia, State of Pennsylvania, have invented or produced a Design for a Shawl-Fabric, of which the following is a specification :

The figure in the accompanying drawings represents sufficient of a shawl to illustrate my design, the portion A of which consists of a series of inclined parallel lines of peculiar character, each line being thicker at some points than at others, and these thick and thin points of the lines being so arranged that the design has the waved appearance shown in the drawings. This design may extend throughout the entire shawl-fabric, or broad strips of this pattern may be alternated with variegated stripes D, composed of a series of minor stripes of any desired color or

arrangement, or the design composed of inclined lines may be arranged in strips B B', the inclination of the lines of one strip being the reverse of that of the lines of the adjoining strip.

I claim—

1. The design, composed of inclined lines, thicker at some points than at others, and arranged as set forth.

2. A shawl-pattern, in which strips of the said inclined lines are alternated with variegated stripes, substantially as described and as illustrated in and by the accompanying drawings.

In testimony whereof I have signed my name to this specification in the presence of two subscribing witnesses.

Witnesses: JOSEPH HODGSON.
